Attorney.

UNITED STATES PATENT OFFICE.

JOHANNES EHRHORN HJORT, OF COPENHAGEN, DENMARK.

CYLINDRICAL MORTISE LATCH.

1,414,019.

Specification of Letters Patent. Patented Apr. 25, 1922.

Application filed May 2, 1921. Serial No. 466,127.

To all whom it may concern:

Be it known that I, JOHANNES EHRHORN HJORT, manufacturer, subject of the King of Denmark, residing at Copenhagen, Denmark, have invented certain new and useful Improvements in Cylindrical Mortise Latches, of which the following is a specification.

The present invention relates to such mortise latches, as are used for doors, furniture, etc., and are opened by means of a knob or handle. The latch here referred to belongs to the known type of such latches in which the mainly cylindrical casing is made extremely compact in order to render practicable the insertion of the latch into a cylindrical hole bored in the stile of the door, instead of, as in the case of the ordinary box-shaped mortise latches, in a mortise gouged in the stile. In the first place the latch proper will thereby be much cheaper to manufacture and, in the second place, the joinery work required for fitting the latch in position will also be considerably cheaper and easier.

Latches of the said known kind have heretofore not been fitted with a spiral spring for keeping the hub of the knob-spindle and, thereby, the knob or handle in normal position, as long as the lock is not being operated. The object of such a spiral spring is to secure the knob or handle in such a position, that when turned, it will at once unlatch the door or, in other words, that the knob or handle will be returned into the normal position by means of the spiral spring, independently of the position of the latch. This spring is well known from ordinary locks, but in case of latches to be opened by means of a knob or handle, it has not heretofore been practicable to use a spiral spring, because the construction of the latch has to be very compact, and it is desired to maintain the cylindrical shape so that fitting of the latch will only require a round (cylindrical) hole to be bored in the edge of the door.

By the present invention the advantage is attained that cylindrical latches may be provided with a spiral spring by disposing the same between the hub and the latch in such a manner, that it will be located in a plane passing through the axis of the latch casing and so that the axis of the spring will intersect the axis of the latch casing. The latch retains thus its compact shape, and preserves all the advantages presented by

the ordinary door-latches fitted with spiral springs, for instance the advantage that the position of the knob or handle will not depend on the latch being withdrawn or not, but will always be a certain definite one, and the motion of the knob or handle required in opening or closing the latch may be made as small as possible by disposing the nose on the hub, which serves to withdraw the latch during the unlatching operation, in such a manner that the angular path which the said nose must follow in order to be moved backwards so far that the latch will be withdrawn into the casing, will be bisected by a plane through the axis of the hub and at right angle to the longitudinal axis of the latch-casing.

Hereby a cheap practical light and compact latch is provided, combining the advantages of the cylindrical latch with the advantages of the ordinary mortise latch.

On the drawing,

Fig. 1 shows the latch in side elevation with the cover removed,

Fig. 2 the latch in top view with the cover in position, and

Fig. 3 the latch viewed from its inner end.

Referring to the drawing, 1 is the front plate which is sunk into the edge of the door-stile, and 2 is the casing which consists of two parts symmetrical about a vertical central plane, the two parts being shaped in such a manner—as it appears from Fig. 3—that the casing may easily be inserted into a bored hole. In contradistinction to the heretofore known latches of this kind, the casing has flat sides, however, whereby it becomes practicable to let the moving parts of the latch be guided against the inner face of the casing proper. 3 is the latch which has a tail 4 extending back into the casing, the said extension being guided by a lug 14, which engages a long slot 15 in the top side of the casing. A similar slot 15' is provided in the bottom side of the casing. A slot in the latch tail is engaged by the upwardly directed finger 6 of the hub 5. The latch is maintained in the latching position by means of a helical spring 7 which is inserted between the inner face of the latch and a fixed cross wall 8 in the casing.

Immediately behind this cross wall, there is provided a spiral spring 9, the free end of which engages another finger 10 on the hub, the said finger being thereby pressed down towards the bottom side of the cas-

ing. The knob or handle attached to the hub will therefore always have a tendency to return into its normal position, independently of the position occupied by the latch 5 proper, all provided that the latch is not at the moment concerned being withdrawn by means of the hub. Behind the hub there is provided still another cross wall 11 in the casing, the said wall closing the rear end of 10 the casing and holding its parts together by means of rivets 12. In order to join the two halves of the casing similar rivets may be provided on the cross-wall 8, as shown on the drawing, or one half of the casing may 15 engage into a recess in the front plate alongside the latch, and may thereby be attached to the front plate.

Owing to its very compact shape, in respect to width as well as length, this latch 20 weakens the door stile only very slightly. In the case of heavy stiles, the latch may be inserted in a single bored hole, while in thinner stiles two holes of smaller diameter may be bored, one on top of the other, so 25 as to correspond to the outer shape of the top and bottom sides of the casing.

Owing to its shape being symmetric about a horizontal plane through its axis, the latch, which is shown as a right-hand latch, may 30 be converted into a left-hand latch simply by substituting for the latch a left-hand latch and by reversing the hub 5 and the spring 9 about the axis of the casing.

I declare that what I claim is:—

35 1. A lock, comprising a substantially cylindrical casing; a latch slidably fitted therein; a spring for moving the latch outwardly of the casing; a hub rotatably mounted in said casing in rear of said spring and having 40 means for retracting the latch; and a spiral spring, separate from the first spring, disposed between the latter and the hub in a vertical plane axial of the casing, with its axis intersecting the casing axis, said spiral 45 spring directly engaging said hub to return the same to normal position independently of the position of the latch.

2. A lock, comprising a substantially cylindrical casing having a central, longitudinal slot; a latch slidably fitted in the casing and formed with a rearwardly-extending tail terminating in a vertical guide lug which projects into said slot, said tail being provided with a slot located in line with the first slot and immediately in front of said lug; a spring operative on said latch to project it outwardly of the casing; and a hub rotatably mounted in said casing and having a finger which extends through the latch slot to engage said lug and thereby retract the latch when the hub is rotated in one direction.

3. A lock, comprising a substantially cylindrical casing having a central, longitudinal slot; a latch slidably fitted in the casing and formed with a rearwardly-extending tail terminating in a vertical guide lug which projects into said slot, said tail being provided with a slot located in line with the first slot and immediately in front of said lug; a spring operative on said latch to project it outwardly of the casing; a hub rotatably mounted in the casing and having a pair of fingers, one directed upwardly and the other directed downwardly, one of said fingers extending through the latch slot to engage said lug and thereby retract the latch when the hub is rotated in one direction; and a spring, separate from the first spring, operative upon the other finger to return said hub to normal position independently of the position of the latch.

4. A lock, as claimed in claim 3, in which the second-named spring has the form of a spiral and is located between the first spring and the hub in a vertical plane which is axial of the casing, with its axis intersecting the casing axis.

In testimony whereof I affix my signature.

JOHANNES EHRHORN HJORT.
